[57] CLAIM

The ornamental design for an inflatable arm water wings for a swimmer, as shown and described.

DESCRIPTION

FIG. 1 is a perspective view of a swimmer, shown by phantom lines, wearing a pair of arm water wings showing my new design;

FIG. 2 is a front perspective view of an inflatable water wing showing my new design, an inflation orifice being shown by phantom lines;

FIG. 3 is a side elevational view of the water wing of FIG. 2 as viewed from the left, the side elevational from the right being a mirror image of FIG. 3;

FIG. 4 is a top plan view of a water wing of FIG. 2;

FIG. 5 is a rear elevational view of a water wing as shown in FIG. 2; and,

FIG. 6 is a front elevational view of a water wing of FIG. 2.
